UNITED STATES PATENT OFFICE.

ALEXANDER CHRZANOWSKI, OF BALTIMORE, MARYLAND.

CLOCK-CASE.

1,363,311.

Specification of Letters Patent. Patented Dec. 28, 1920.

Application filed October 8, 1918. Serial No. 257,424.

To all whom it may concern:

Be it known that I, ALEXANDER CHRZANOWSKI, a citizen of the United States, residing at Baltimore, in the State of Maryland, have invented certain new and useful Improvements in Clock-Cases, of which the following is a specification.

This invention relates to improvements in clock cases and has for its object to provide a case in which a clock can be placed for the purpose of increasing the alarm; also to give an ornamental appearance to the clock.

The invention consists of the novel construction and arrangement of the parts and combination of parts hereinafter more fully set forth in the following specification and pointed out in detail in the appended claim.

In the accompanying drawing,—

Figure 1 is a front view of my invention with a clock in position therein.

Fig. 2 is a top plan view of Fig. 1.

Fig. 3 is a side elevation of Fig. 1.

Fig. 4 is a vertical section of Fig. 1, with the front partly opened.

Referring to the accompanying drawings, forming part of this specification, and in which like reference numerals designate like parts throughout the several views, 1 designates a metal casing having a star-shaped door 2 pivoted thereto at 3. The said door 2 has an opening 4 in the center thereof which is covered with a piece of

glass 5. In the top of the casing 1 is an opening with a cover 6 adapted to open or close said opening to allow the sound of the alarm to escape from said casing. At the back of the casing is a flat metal piece 7 having apertures 8 therein by means of which the case may be hung on a nail or other suitable device. A handle 9 has one end secured to the top of the casing 1 and the other end secured to the metal piece 7. Within the case 1 is a rod 10 upon which the clock rest 11 is mounted, said rest 11 being adapted to be adjusted up and down on said rod 10 to bring the clock directly in front of the opening in the front of the casing. The said rest 11 is provided with a set screw 12 by means of which the rest is held in the desired position on the rod 10.

Having thus described my invention, what I claim is:

A clock casing having an opening in the top thereof, a pivoted cover for said opening, a hinged front for said casing, a vertical rod within said case at the rear thereof, a clock rest having an aperture in the rear thereof through which the said vertical rod projects, and a set screw to hold the said rest in the desired position on said rod.

In testimony whereof I affix my signature.

ALEXANDER CHRZANOWSKI.
